ABSTRACT

A fastener driver includes a housing, a cylinder disposed within the housing, and a piston positioned and moveable within the cylinder. The fastener driver additionally includes a nosepiece at least partially defining a fastener driving track through which fasteners are driven, and a driver blade attached to the piston and moveable with the piston to drive the fasteners through the fastener driving track. The driver blade includes an axial guiding projection for guiding the driver blade within the nosepiece, and wherein the projection terminates before a distal end of the driver blade.

POWERED FASTENER DRIVER**CROSS-REFERENCE TO RELATED APPLICATIONS**

This application is a divisional of U.S. patent application Ser. No. 16/776,173 filed on Jan. 29, 2020, now U.S. Pat. No. 11,130,221, which claims priority to U.S. Provisional Patent Application No. 62/799,141 filed on Jan. 31, 2019, the entire contents of which are incorporated herein by reference.

FIELD OF THE INVENTION

The present invention relates to powered fastener drivers, and more particularly to a driver blade and nosepiece for use with a powered fastener driver.

BACKGROUND OF THE INVENTION

There are various fastener drivers known in the art for driving fasteners (e.g., nails, tacks, staples, etc.) into a workpiece. These fastener drivers operate utilizing various means known in the art (e.g., compressed air generated by an air compressor, electrical energy, a flywheel mechanism, etc.) to drive a driver blade from a top-dead-center position to a bottom-dead-center position.

SUMMARY OF THE INVENTION

The invention provides, in one aspect, a fastener driver including a housing, a cylinder disposed within the housing, a piston positioned and moveable within the cylinder, a nosepiece at least partially defining a fastener driving track through which fasteners are driven, and a driver blade attached to the piston and moveable with the piston to drive the fasteners through the fastener driving track. The driver blade includes an axial guiding projection for guiding the driver blade within the nosepiece. The projection terminates before a distal end of the driver blade.

The invention provides, in another aspect, a fastener driver including a housing, a cylinder disposed within the housing, a piston positioned and moveable within the cylinder, a driver blade attached to the piston and moveable with the piston from a first position toward a second position during a fastener driving operation, and a nosepiece at least partially defining a fastener driving track through which fasteners are driven by the driver blade. The nosepiece includes a longitudinal guide groove in which a fastener is received and parallel ribs extending from an interior surface of the nosepiece, thereby defining an extension of the guide groove. When the driver blade is in the second position, the driver blade partially overlaps with the guide ribs, thereby allowing a first portion of the fastener to be received in the guide ribs and a lower, second portion of the fastener to be received in the guide groove.

The invention provides, in another aspect, a fastener driver including a housing, a cylinder disposed within the housing, a piston positioned and moveable within the cylinder, a driver blade attached to the piston and moveable with the piston from a first position toward a second position during a fastener driving operation, and a nosepiece at least partially defining a fastener driving track through which fasteners are driven by the driver blade, wherein when the driver blade is in the second position, the driver blade partially overlaps with a portion of the nosepiece, and a ratio

of a length from a crown of one of the fasteners to a distal end of the nosepiece to a total length of the fastener driver is less than 25%.

Other features and aspects of the invention will become apparent by consideration of the following detailed description and accompanying drawings.

BRIEF DESCRIPTION OF THE DRAWINGS

FIG. 1 is a perspective view of a powered fastener driver in accordance with an embodiment of the invention.

FIG. 2 is a perspective view of a nosepiece assembly of the powered fastener driver of FIG. 1.

FIG. 3 is a perspective view of the nosepiece assembly of the powered fastener driver of FIG. 1, with a nosepiece removed.

FIG. 4 is an enlarged perspective of the nosepiece assembly of the powered fastener driver of FIG. 1.

FIG. 5A is a bottom perspective view of the nosepiece and a driver blade of the powered fastener driver of FIG. 1.

FIG. 5B is a cross-sectional view of the nosepiece and driver blade of FIG. 5A.

FIG. 6A is a bottom perspective view of the nosepiece of the powered fastener driver of FIG. 1, illustrating a fastener in a fastener driving track.

FIG. 6B is a reverse perspective view of the nosepiece and fastener of FIG. 6A.

FIG. 7 is a perspective view of the driver blade of the powered fastener driver of FIG. 1.

FIG. 8 is a bottom perspective view of the nosepiece of the powered fastener driver of FIG. 1.

FIG. 9 is a side view of the fastener driver of FIG. 1.

FIG. 10 is a front view of the nosepiece assembly of FIG. 2, with portions removed.

FIG. 11 is a bottom perspective view of the nosepiece and collated fasteners received in a fastener driving track of the nosepiece.

FIG. 12 is a plan view of the nosepiece and collated fasteners of FIG. 11.

FIG. 13 is another plan view of the nosepiece and collated fasteners of FIG. 11.

FIG. 14 is a side view of a powered fastener driver in accordance with another embodiment of the invention.

FIG. 15A is a bottom perspective view of a nosepiece and a driver blade of the powered fastener driver of FIG. 14.

FIG. 15B is a cross-sectional view of the nosepiece and driver blade of the powered fastener driver of FIG. 14.

FIG. 16 is a perspective view of the driver blade of the powered fastener driver FIG. 14.

FIG. 17 is a bottom perspective view of the nosepiece of the powered fastener driver of FIG. 14.

FIG. 18 is a plan view of the nosepiece and collated fasteners of FIG. 14.

Before any embodiments of the invention are explained in detail, it is to be understood that the invention is not limited in its application to the details of construction and the arrangement of components set forth in the following description or illustrated in the following drawings. The invention is capable of other embodiments and of being practiced or of being carried out in various ways. Also, it is to be understood that the phraseology and terminology used herein is for the purpose of description and should not be regarded as limiting.

DETAILED DESCRIPTION

With reference to FIG. 1, a gas spring-powered fastener driver 10 is operable to drive fasteners (e.g., nails, tacks,

staples, etc.) held within a magazine 14 into a workpiece. The fastener driver 10 includes a cylinder 18. A moveable piston (not shown) is positioned within the cylinder 18. With reference to FIG. 2, the fastener driver 10 further includes a driver blade 22 that is attached to the piston and moveable therewith. The fastener driver 10 does not require an external source of air pressure, but rather includes pressurized gas in the cylinder 18.

With reference to FIG. 1, the fastener driver 10 includes a housing 26 having a cylinder housing portion 30 and a motor housing portion 34 extending therefrom. The cylinder housing portion 30 is configured to support the cylinder 18, whereas the motor housing portion 34 is configured to support a motor 38 and a transmission 42 downstream of the motor 38. In addition, the illustrated housing 26 includes a handle portion 46 extending from the cylinder housing portion 30, and a battery attachment portion 50 coupled to an opposite end of the handle portion 46. A battery (not shown) is electrically connectable to the motor 38 for supplying electrical power to the motor 38. The handle portion 46 supports a trigger (not shown), which is depressed by a user to initiate a driving cycle of the fastener driver 10.

With reference to FIG. 3, the driver blade 22 defines a longitudinal axis 58. During a driving cycle, the driver blade 22 and piston are moveable between a top-dead-center (TDC) or ready position within the cylinder 18, and a bottom-dead-center (BDC) or driven position, along the axis 58. The fastener driver 10 further includes a lifter assembly (not shown), which is powered by the motor 38 (FIG. 1), and which is operable to return the driver blade 22 from the driven position to the ready position.

The fastener driver 10 further includes a nosepiece assembly 62 that receives collated fasteners from the magazine 14 (FIGS. 2 and 4). The nosepiece assembly 62 includes a nosepiece 66 and a shear block 70 that collectively define a fastener driving channel or track 80 (FIGS. 6A, 6B, and 8) that guides the fasteners as they are driven into a workpiece by the driver blade 22. The shear block 70 further defines an opening (not shown) that permits fasteners to pass from the magazine 14 through the shear block 70 and into the driver track 80.

With reference to FIGS. 5A, 5B, and 7, the driver blade 22 includes an elongated body 74 having a first planar surface (i.e., a front surface 78) and an opposite, a second planar surface (i.e., a rear surface 82). A first edge 86 extends between the front surface 78 and the rear surface 82 along one lateral side of the body 74, and a second edge 90 extends between the front surface 78 and the rear surface 82 along an opposite lateral side of the body 74. The front surface 78 is parallel to the rear surface 82. Likewise, the edges 86, 90 are also parallel.

The driver blade 22 includes a plurality of lift teeth 94 formed along the first edge 86 of the body 74. The first edge 86 extends in the direction of the axis 58, and the lift teeth 94 project from the first edge 86 in a direction transverse to the axis 58. The lift teeth 94 are sequentially engaged with the lifter assembly during the return of the driver blade 22 from the driven position to the ready position. In addition, the driver blade 22 includes a plurality of projections 98 extending from the second edge in a direction transverse to the axis 58. In one embodiment, the plurality of projections 98 are configured to engage a latch (not shown) of the fastener driver 10 for inhibiting the driver blade 22 from moving toward the driven position.

The driver blade 22 further includes a first end 22a and a second end, or distal end 22b opposite the first end 22a. The

front and rear surfaces 78, 82, and the first and second edges 86, 90, extend between the first and second ends 22a, 22b. In the illustrated embodiment of the driver blade 22, the first end 22a includes an aperture 100 for receiving a fastener (e.g., screw, bolt, etc.) for connection with the piston. The second end 22b of the driver blade 22 is oriented perpendicular to the axis 58 for striking fasteners fed from the magazine 14 and driving the fasteners into a workpiece. The driver blade 22 additionally includes an elongated recess 106 extending along the front surface 78 (i.e., the surface facing the nosepiece 66) of the driver blade 22, the purpose of which is described below.

With reference to FIG. 7, the driver blade 22 includes a guiding projection 110 positioned on the elongated body 74. The guiding projection 110 is parallel with the longitudinal axis 58 of the driver blade 22 and also extends in a direction that is transverse to the axis 58 to be received within a corresponding recess 114 (FIGS. 4, 6A, 6B, and 8) within the nosepiece 66 to provide lateral stability to the driver blade 22 as it reciprocates between its ready and driven positions. The guiding projection 110 is located near the second end 22b of the driver blade 22 and terminates before the distal end 22b of the driver blade 22, creating a gap 112 between the guiding projection 110 and the distal end 22b (FIG. 7). This allows for the driver blade 22 to be guided within the nosepiece 66, but also prevents the projection 110 from contacting the work surface with the driver blade 22. As such, the guiding projection 110 does not cause a "mar" or "indentation" on the work surface as a fastener (i.e., staple 102) is driven into the surface.

The nosepiece 66 includes an elongated body 118 having a first planar surface, or front surface 122 and an opposite, second planar surface, or rear surface 126, such that the front surface 122 is parallel to the rear surface 126. The nosepiece 66 further includes an elongated guide groove 130 within the rear surface 126 extending parallel with the axis 58 that partially defines the fastener driver track 80 (FIGS. 6A and 6B). The guide groove 130 is sized to receive the width of the driver blade 22 (below the last of the teeth 94 and projections 98) and the staples 102 to provide lateral stability to the staples 102 as they are driven from the nosepiece assembly 62 (FIG. 4). The recess 114 in which the guiding projection 110 is received is also located in the guide groove 130.

With reference to FIGS. 6A, 6B, and 8, the nosepiece 66 includes guide ribs 134 extending along the rear surface 126 of the nosepiece 66, such that the ribs 134 are substantially parallel to each other. The space between the ribs 94 defines an extension of the guide groove 130 and provides additional lateral support for the staples 102 during a firing operation. Specifically, when in the fastener driver track 80, an upper portion 102a of the staple 102 is supported by the guide ribs 134 and a lower portion 102b of the staple 102 is supported within the guide groove 130. The nosepiece 66 additionally includes laterally extending ribs 138 connecting opposite sides of the nosepiece 66 with the respective ribs 134. The laterally extending ribs 138 are oriented perpendicular relative to the guide ribs 134. In alternative embodiments (FIGS. 14-18), the laterally extending ribs 138 may be omitted.

More specifically, and with reference to the illustrated embodiment of the fastener driver 10 of FIGS. 11-13, the staple 102 includes a length L1 of approximately 37.75 mm. The guide ribs 134 include a length L2 of 13.25 mm and the guide groove 130 includes a length L3 of 31.20 mm. Furthermore, a distance D1 from a crown of the staple 102 to a distal end of the guide rib 134 is approximately 5.5 mm.

When the staple 102 is loaded from the magazine 14 into the fastener driving track 80, the guide ribs 134 support approximately 13.25 mm, or 35%, of the length of the staple 102 (coinciding with length L2). Additionally, the guide groove 130 supports approximately 21.00 mm, or 55%, of the length L1 of the staple 102 (coinciding with length L3). As such, in total, approximately 34.25 mm, or 90%, of the length L1 of the staple 102 is supported by a combination of the guide ribs 134 and the guide groove 130, leaving the remaining 10% of the length L1 of the staple 102 unsupported and extending beyond the distal ends of the guide ribs 134 (coinciding with distance D1).

FIGS. 14-18 illustrate an alternative embodiment of a fastener driver 10', with like parts as the fastener driver 10 of FIGS. 1-13 being shown with like reference numerals plus a prime marker (').

The fastener driver 10' includes a driver blade 22' that is attached to a piston and moveable therewith. The fastener driver 10' further includes a nosepiece assembly 62' including a nosepiece 66' and a shear block (not shown, similar to the shear block 70 shown in FIGS. 2-3) that collectively define a fastener driving channel or track 80' (FIG. 17) that guides fasteners as they are driven into a workpiece by the driver blade 22'.

With reference to FIG. 16, the driver blade 22' includes an elongated recess 106' extending along a front surface 78' (i.e., the surface facing the nosepiece 66') of the driver blade 22'. The elongated recess 106' includes a portion 108' having a greater width than the rest of the recess 106', the purpose of which is described below.

With reference to FIGS. 17-18, the nosepiece 66' includes a guide groove 130' sized to receive the width of the driver blade 22' (below the last of teeth 94' and projections 98' of the driver blade 22') and staples 102' to provide lateral stability to the staples 102' as they are driven from the nosepiece assembly 62'. The nosepiece 66' additionally includes guide ribs 134' extending along a rear surface 126' of the nosepiece 66', such that the ribs 134' are substantially parallel to each other. The space between the ribs 94' defines an extension of the guide groove 130' and provides additional lateral support for the staples 102' during a firing operation.

More specifically, and with reference to the illustrated embodiment of the fastener driver 10' of FIG. 18, the staple 102' includes a length L1' of approximately 37.75 mm. The guide ribs 134' include a length L2' of 13.25 mm and the guide groove 130' includes a length L3' of 31.20 mm. Furthermore, a distance D1' from a crown of the staple 102' to a distal end of the guide rib 134' is approximately 5.5 mm. When the staple 102' is loaded into the fastener driving track 80', the guide ribs 134' support approximately 13.25 mm, or 35%, of the length of the staple 102'. Additionally, the guide groove 130' supports approximately 21.00 mm, or 55%, of the length L1' of the staple 102'. As such, in total, approximately 34.25 mm, or 90%, of the length L1' of the staple 102' is supported by a combination of the guide ribs 134' and the guide groove 130', leaving the remaining 10% of the length L1' of the staple 102' unsupported and extending beyond the distal ends of the guide ribs 134'.

As the driver blade 22' moves from the ready position to the driven position (with the driven position being shown in FIGS. 15A and 15B), the guide ribs 134' of the nosepiece 66' slide within the enlarged portion 108' of the elongated recess 106' in the driver blade 22' (FIGS. 15B and 16). Because the driver blade 22' overlaps the guide ribs 134' in this manner, the overall height of the fastener driver 10' is reduced, compared to a prior art fastener driver in which the majority

of the length of the fasteners is supported within the guide groove 130'. In some embodiments of the fastener driver 10', the ratio of a length L4' from the crown of the staple 102' to a distal end of the nosepiece 66' (FIG. 18) to a total length L5' of the tool 10' (FIG. 14) is less than 25%. In the illustrated embodiment of the fastener driver 10', the length L4' is 57.5 mm (FIG. 18), and the total length L5' of the tool 10' is 263.3 mm (FIG. 14). As such, the ratio of L4':L5' is approximately 22%.

Various features of the invention are set forth in the following claims.

What is claimed is:

1. A fastener driver comprising:
a housing;
a cylinder disposed within the housing;
a piston positioned and moveable within the cylinder;
a nosepiece at least partially defining a fastener driving track through which fasteners are driven; and
a driver blade having a first distal end and a second distal end opposite the first end, the driver blade attached to the piston proximate the first distal end and moveable with the piston to drive the fasteners through the fastener driving track;
wherein the driver blade includes an axial guiding projection for guiding the driver blade within the nosepiece, wherein the projection includes a first end that terminates before the first distal end of the driver blade and a second end that terminates before the second distal end of the driver blade, and
wherein the first end of the projection is raised relative to a surface of the driver blade defined between the first end of projection and the first distal end of the driver blade, such that the axial guiding projection only extends along a portion of the driver blade.

2. The fastener driver of claim 1, wherein the axial guiding projection is oriented parallel with a longitudinal axis of the driver blade.

3. The fastener driver of claim 2, wherein the axial guiding projection extends from the driver blade in a direction transverse to the longitudinal axis.

4. The fastener driver of claim 3, wherein the nosepiece includes a recess extending along a length of the nosepiece, and wherein the recess is configured to receive the axial guiding projection.

5. The fastener driver of claim 4, wherein the nosepiece includes a longitudinal guide groove in which the fasteners are received, and wherein the longitudinal guide groove at least partially defines the fastener driving track.

6. The fastener driver of claim 5, wherein the nosepiece includes parallel guide ribs extending from an interior surface of the nosepiece, thereby defining an extension of the guide groove.

7. The fastener driver of claim 6, wherein the recess in which the axial guiding projection of the driver blade is received extends is positioned within the longitudinal guide groove and between the parallel guide ribs.

8. The fastener driver of claim 6, wherein the fastener driving track is defined at least partially by the longitudinal guide groove and the parallel guide ribs.

9. The fastener driver of claim 1, wherein the driver blade includes an elongated recess extending along a surface of the driver blade facing the nosepiece, and wherein the elongated recess extends at least partially between the first end of the axial guiding projection and the first distal end of the driver blade.

10. The fastener driver of claim 9, wherein the driver blade is movable from a first position toward a second

position during a fastener driving operation, wherein in the first position of the driver blade, an upper portion of the fastener within the fastener driving track is received between the parallel guide ribs and a lower portion of the fastener is received in the guide groove, and wherein when the driver blade is in the second position, the parallel guide ribs are at least partially received within the elongated recess in the driver blade.

11. The fastener driver of claim 10, wherein a ratio of a length from a crown of one of the fasteners to a distal end of the nosepiece to a total length of the fastener driver is less than 25%.

12. The fastener driver of claim 10, wherein when the driver blade is in the second position, the nosepiece supports approximately 90% of the length of the one of the fasteners. 15

13. A fastener driver comprising:

a housing;

a cylinder disposed within the housing;

a piston positioned and moveable within the cylinder;

a nosepiece at least partially defining a fastener driving track through which fasteners are driven, the nosepiece including

a longitudinal guide groove extending along a first length of the nosepiece to at least partially define the fastener driving track in which the fasteners are received, the longitudinal guide groove configured to provide lateral support to a lower portion of the fastener, and

parallel guide ribs extending from an interior surface of the nosepiece along a second length of the nosepiece, thereby defining an extension of the guide groove, the parallel guide ribs configured to provide lateral support to an upper portion of the fastener; and

a driver blade attached to the piston and moveable with the piston to drive the fasteners through the fastener driving track;

wherein the driver blade includes an axial guiding projection for guiding the driver blade within the nosepiece, and wherein the projection terminates before a distal end of the driver blade,

wherein the first and second lengths are less than a total length of the nosepiece.

14. The fastener driver of claim 13, wherein the axial guiding projection is oriented parallel with a longitudinal axis of the driver blade.

15. The fastener driver of claim 14, wherein the axial guiding projection extends from the driver blade in a direction transverse to the longitudinal axis.

16. The fastener driver of claim 15, wherein the nosepiece includes a recess extending along a length of the nosepiece, and wherein the recess is configured to receive the axial guiding projection.

17. The fastener driver of claim 13, wherein the driver blade includes a first distal end and the distal end is a second distal end opposite the first end, and wherein the projection

includes a first end that terminates before the first distal end of the driver blade and a second end that terminates before the second distal end of the driver blade so the axial guiding projection extends along a portion of the driver blade.

18. The fastener driver of claim 13, wherein the parallel guide ribs are positioned laterally outside the longitudinal guide groove.

19. A fastener driver comprising:

a housing;

a cylinder disposed within the housing;

a piston positioned and moveable within the cylinder; a nosepiece at least partially defining a fastener driving track through which fasteners are driven, the nosepiece including

a longitudinal guide groove at least partially define the fastener driving track in which the fasteners are received, the longitudinal guide groove configured to provide lateral support to a lower portion of the fastener,

parallel guide ribs extending from an interior surface of the nosepiece, thereby defining an extension of the guide groove, the parallel guide ribs configured to provide lateral support to an upper portion of the fastener, and

laterally extending ribs connecting opposite sides of the nosepiece to respective parallel guide ribs; and

a driver blade attached to the piston and moveable with the piston to drive the fasteners through the fastener driving track;

wherein the driver blade includes an axial guiding projection for guiding the driver blade within the nosepiece, and wherein the projection terminates before a distal end of the driver blade.

20. The fastener driver of claim 19, wherein the longitudinal guide groove extends along a first length of the nosepiece, wherein parallel guide ribs extends from an interior surface of the nosepiece along a second length of the nosepiece, and wherein the first and second length are less than a total length of the nosepiece.

21. The fastener driver of claim 19, wherein the nosepiece includes a recess extending along a length of the nosepiece, and wherein the recess is configured to receive the axial guiding projection.

22. The fastener driver of claim 19, wherein the nosepiece has a first end and a second end opposite the first end, the longitudinal guide groove defines a first width between the first end and the laterally extending ribs, the nosepiece defines a second width between the laterally extending ribs and the second end, and the second width is greater than the first width.
